UNITED STATES PATENT OFFICE.

WILLIAM S. WOOD, OF CHICAGO, ILLINOIS, ASSIGNOR OF THREE-FOURTHS
TO SARA S. HARRIS, OF CHICAGO, ILLINOIS.

APPARATUS FOR MAKING MOLDS.

SPECIFICATION forming part of Letters Patent No. 747,289, dated December 15, 1903.

Application filed November 22, 1902. Serial No. 132,413. (No model.)

To all whom it may concern:

Be it known that I, WILLIAM S. WOOD, a citizen of the United States, residing at Chicago, in the county of Cook and State of Illinois, have invented certain new and useful Improvements in Apparatus for Making Molds, of which I do declare the following to be a full, clear, and exact description, reference being had to the accompanying drawings, forming part of this specification.

The invention relates to molding apparatus, and seeks to provide a simple and effective reversible molding apparatus, which is preferably portable, whereby molds for castings may be quickly and conveniently made; and the invention consists in the features of construction, arrangements, and combinations of parts hereinafter described, illustrated in the accompanying drawings, and more particularly pointed out in the appended claims.

In the drawings, Figure 1 is a vertical section of the improved apparatus in position with the flask filled with sand. Fig. 2 is a similar view with the position of the parts reversed and with the patterns drawn from the mold. Fig. 3 is a detail inverted plan view of the stripping-plate. Fig. 4 is an inverted plan view of the pattern or main supporting plate.

The improved apparatus comprises a flat reversible stripping-plate adapted to fit over the open side of the flask G. When the parts are in position for ramming the sand into the flask G, the latter is mounted upon the stripping-plate A, (see Fig. 1,) and in order that the flask may be placed in proper position it is provided with keys g, adapted to enter suitable holes a⁵ (see Fig. 3) in opposite ends of the stripping-plate A.

The reversible stripping-plate A is provided with openings a³, which conform in outline to the particular pattern employed and through which the patterns may be projected. If the pattern is gated, the separate openings a³ are connected by a slot a⁴, through which the gate of the pattern extends. In order that the stripping-plate may be readily adapted for use in connection with different patterns, the openings a³ are preferably formed in a bodily-removable rectangular section A', which fits within a central rectangular opening in the main body of the

stripping-plate A. The edges of the section A' and the edges of the opening in the stripping-plate are rabbeted, as shown, and the section A' is removably held in place by screws a². For convenience in reversing the apparatus stripping-plate A is provided with laterally-extending handles A², which may be readily grasped by the molder.

The main or pattern-supporting plate B is connected to the stripping-plate A and is reversible therewith. This supporting-plate is positioned against the face of the stripping-plate A and extends over the openings a³ therein. Besides being reversible with the stripping-plate A the supporting-plate B is movable laterally to and from the stripping-plate A and at right angles thereto to draw the pattern. To insure the right-line movement of the pattern-supporting plate B and to assist the molder in drawing the patterns without damage to the molds, laterally-projecting guide-pins a are fixed to the stripping-plate A, and sleeves b, surrounding the pins a, are fixed to the pattern-supporting plate B.

The patterns C (which in this instance are separate halves of a pulley) are fixed to the supporting-plate B and extend through the openings a³ in the stripping-plate A. Preferably plates or mounts D for the patterns are interposed between the supporting-plate B and the patterns C, which are equal in size to the openings a³ in the stripping-plate A and which are equal in thickness to the stripping-plate. The patterns are usually connected by a gate c, which extends through the slot a⁴ in the stripping-plate.

The patterns C are preferably fixed to a rectangular bodily-removable section B', set within a central rectangular opening in the supporting-plate B. The edges of the opening and the edges of the removable section B' are rabbeted, and the latter is removably held in place by screws b². (See Fig. 4.)

When the sand is rammed into the mold, the apparatus is placed in the position shown in Fig. 1, with the main supporting-plate B resting upon a pair of suitable cross bars or stringers F or otherwise rigidly mounted, so that the stripping-plate A and flask G may be supported thereby in convenient position,

so that the patterns C, which are secured directly to the supporting-plate B, are firmly held in position during the ramming operation. As soon as the flask is filled with sand 5 packed about the patterns C the bottom board G' is placed upon the flask and the apparatus reversed into the position shown in Fig. 2. The patterns may then be easily and quickly drawn without damaging the molds by shifting 10 the supporting-plate B at right angles to the stripping-plate, the movement of the stripping-plate being accurately guided by the pins a. By thus reversing the apparatus all danger of parts of the mold falling out 15 when the pattern is drawn is obviated.

For drawing the pattern the supporting-plate B is preferably provided with a handle B², rigidly secured thereto, which may be grasped by the operator with one hand as he 20 taps the supporting-plate with a hammer or piece of iron held in the other hand. In this manner the operator is able to feel, as it were, the instant the pattern separates from the sand and is able to regulate the drawing 25 of the pattern more effectively than if any mechanical device, such as a screw or lever, were employed to shift the supporting-plate B. It will also be observed that as the patterns 30 commence to move from the molds the supporting-plate B is against the face of the stripping-plate A and close to the fixed ends of the guide-pins a, so that at the instant the patterns start from the mold the supporting-plate B is securely held by pins a against any 35 lateral shift.

Preferably stops E are adjustably threaded upon the ends of the guide-pins a and are held in adjusted position by lock-nuts E', so that when the patterns have been entirely 40 lifted from the molds, as indicated in Fig. 2, the sleeves b upon the supporting-plate B will engage the stops E, and the further movement of the supporting-plate will lift the stripping-plate A clear of the flask and 45 of the mold therein.

While the present invention is particularly designed as a portable apparatus for bench-work, changes could be made in the arrangement of parts and details of structure without departure from the essentials of the invention.

Having described my invention, what I claim as new, and desire to secure by Letters Patent, is—

55 1. A portable, reversible molding apparatus comprising a main supporting-plate for the apparatus, a pattern fixed to said plate and a stripping-plate surrounding the pattern, said plates being in movable engagement one with 60 the other.

2. A portable, reversible molding apparatus comprising a main supporting-plate, a pattern fixed to said plate, a stripping-plate surrounding such pattern and guide-pins extending 65 between said plates for controlling the shift of said supporting-plate to draw the patterns.

3. A portable, reversible molding apparatus

comprising a main supporting-plate for the apparatus, a pattern fixed to said plate, a stripping-plate surrounding such pattern and in 70 movable engagement with said supporting-plate, guides fixed to one of said plates and means fixed to the other of said plates engaging said guides.

4. A portable, reversible molding apparatus 75 comprising a main supporting-plate, a pattern fixed to said plate, a stripping-plate surrounding such pattern and in movable engagement with said supporting-plate, guides fixed to said stripping-plate, means on said supporting-plate engaging said guides and stops fixed to 80 said guides for limiting the movement of said supporting-plate in drawing the pattern.

5. A portable, reversible molding apparatus comprising a main supporting-plate, a pattern 85 fixed to said plate, a stripping-plate surrounding such pattern and in movable engagement with said supporting-plate and a draft-handle rigidly secured to said supporting-plate for drawing the pattern by hand. 90

6. A reversible molding apparatus comprising a flat, reversible stripping-plate adapted to fit over the open side of the flask and having an opening therein through which the pattern is projected, a flat pattern-supporting plate mounted upon and reversible with said stripping-plate, said pattern-supporting plate extending over the opening in said stripping-plate and being movable to and from the same to draw the pattern and laterally-projecting guides extending between said plates whereon said pattern-supporting plate is shifted at right angles to said stripping-plate to draw the pattern. 100

7. A reversible molding apparatus comprising a flat, reversible stripping-plate adapted to fit over the open side of the flask and having an opening therein through which the pattern is projected, a flat pattern-supporting plate mounted upon, extending over the opening therein and reversible with said stripping-plate, a pattern fixed to said supporting-plate and extending through the opening in said stripping-plate, guides extending between said plates whereon said pattern-supporting plate is shifted to draw the pattern. 110 115

8. A reversible molding apparatus comprising a flat, reversible stripping-plate adapted to fit over the open side of the flask and having an opening therein through which the pattern is projected, a flat pattern-supporting plate mounted upon and reversible with said stripping-plate and normally held against its face, a pattern fixed to said supporting-plate and extending through the opening in 120 said stripping-plate, said supporting-plate being adapted to hold the patterns rigidly in position during the ramming operation and being shiftably mounted upon said stripping-plate to draw the patterns. 125 130

9. A reversible molding apparatus comprising a flat, reversible stripping-plate adapted to fit over the open side of the flask and having an opening therein through which the

pattern is projected, a pattern - supporting plate mounted upon and reversible with said stripping-plate, means for guiding said pattern-plate at right angles to and from said 5 stripping-plate and a draft-handle rigidly secured to said supporting-plate for drawing the patterns by hand.

10. A reversible molding apparatus comprising a flat, reversible stripping-plate adapted to fit over the open side of the flask and having an opening therein through which the pattern is projected, a flat pattern-supporting plate mounted upon and reversible with said stripping-plate, said pattern-supporting 15 plate extending over the opening in said stripping-plate and movable to and from the same to draw the pattern, projecting guides fixed to said stripping-plate and means on said supporting-plate engaging said guides to insure 20 right-line movement of said supporting-plate as it is shifted to draw the pattern.

11. A reversible molding apparatus comprising a flat, reversible stripping-plate adapted to fit over the open side of the flask and having an opening therein through which the pattern is projected, a flat pattern-supporting plate mounted upon and reversible with said stripping-plate, said pattern-supporting 25 plate extending over the opening in said stripping-plate and movable to and from the same to draw the pattern, projecting guides fixed to said stripping-plate, means on said supporting-plate engaging said guides and stops on said guides for limiting the movement of said supporting-plate as it is shifted 30 to draw the pattern.

35 12. A molding apparatus comprising a re-

versible stripping-plate adapted to fit over the open side of the flask and having an opening therein through which the pattern may be 40 projected, a pattern-supporting plate mounted on said stripping-plate and extending over said opening, guides extending between said plates whereon said supporting-plate is shifted to draw the pattern, a mount on said pattern-supporting plate equal in thickness to 45 said stripping-plate and adapted to fit within the opening therein and a pattern fixed to said mount.

13. A molding apparatus comprising a flat, 50 reversible stripping-plate adapted to fit over the open side of the flask and having an opening therein through which the pattern is projected, a pattern-supporting plate mounted on and reversible with said stripping-plate 55 and extending over said opening, said pattern-supporting plate having a central bodily-removable section, a pattern fixed to said section and means for guiding said pattern-supporting plate as it is shifted to draw the pattern. 60

14. A molding apparatus comprising a flat, reversible stripping-plate provided with a central, bodily-removable section having an opening therein through which the pattern 65 is projected, and pattern - supporting plate mounted upon and reversible with said stripping-plate and extending over said opening and means for guiding said pattern-support as it is shifted to draw a pattern.
